Primary Examiner — Darlington Ly*Assistant Examiner* — Nasim Abdulaziz Ali(74) *Attorney, Agent, or Firm* — Hamre, Schumann, Mueller & Larson, P.C.(57) **CLAIM**

The ornamental design for a caliper for a disc brake, as shown and described.

DESCRIPTION

FIG. 1 is a top front perspective view of a caliper for a disc brake showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a bottom perspective view thereof; and,

FIG. 9 is a top rear perspective view thereof.

The broken lines depict portions of the caliper for a disc brake in which the design is embodied that form no part of the claimed design.

1 Claim, 9 Drawing Sheets(56)
